UNITED STATES PATENT OFFICE

EDWARD M. HILL, OF BROOKLINE, MASSACHUSETTS, ASSIGNOR TO WHITING-ADAMS COMPANY, OF BOSTON, MASSACHUSETTS, A CORPORATION OF MASSACHUSETTS

METHOD OF MAKING A BRUSH

Application filed November 29, 1929. Serial No. 410,412.

This invention relates to brushes, and more particularly to bristle or hair brushes such as are used for painting and cleaning purposes, and also to a method of making the same. Its general object is to make possible the economical production of a finished article in which the bristles and handle are so firmly secured as to ensure strength and long life.

In the manufacture of such brushes, it has been the custom to engage in opposite ends of a suitable ferrule the butt ends of a bunch of bristles, preferably after they have been bonded together, and the butt portion of a wooden handle. The ferrule was then compressed against the bristles and handle butt. The end of the butt portion was usually formed with pegs which were forced into the bristles and served to expand them tightly against the interior wall of the ferrule. Inasmuch as such pegs must be made of substantial cross-sectional area in order to ensure strength, they tend to push the bristles out of place, especially when heavy rubber cements are used as the bonding agent. When the brush is soaked in water or in other liquids in which the bristles are caused to become swollen, they tend to buckle at their butt ends and to become lose. When the butt ends of the bristles are bonded together with rubber cements which require heat vulcanization, the assembly of the bristles with the handle and ferrule must be made before such vulcanization, and when vulcanization is thus effected, it is found that not only does the handle impede complete vulcanization because of its poor conductivity, but that it shrinks badly under the action of heat and becomes loose. In accordance with the present invention, the butt ends of the bristles, after being suitably bonded together, are inserted in one end of a ferrule which is then preferably contracted to hold the bristles in place. A thin but rigid metal plate having sharp-end prongs struck out in one direction at substantially uniform intervals from its entire body portion is then passed through the other end of the ferrule, with the prongs pointing in the direction of the bristles, and the prongs are driven into the mass of bristles

so that the latter are expanded into tight contact with the interior wall of the ferrule. Upon the setting of the bonding agent, the bristles are firmly anchored in place. The butt portion of the handle may then be driven into the other end of the ferrule against the plate, and a permanent assembly ensured by clamping the ferrule against this portion of the handle. When rubber cements are used as the bonding agent for the butt ends of the bristles, setting and vulcanization of the cement is effected before assembly with the handle. An important advantage of a brush constructed in accordance with the present invention is that it makes possible the employment of more bristles than used in the pegged head type of brush, wherein the pegs occupy a substantial portion of the cross-sectional area of the bristles.

With these and other features and objects in view, the invention will now be described in conjunction with certain embodiments thereof, shown on the accompanying drawing, wherein

Figure 1 is a front view of an oval type of brush constructed in accordance with the present invention.

Figure 2 is a side view of a pronged plate suitable for this type of brush.

Figure 3 represents a fragmentary section through a partly assembled brush, and more particularly at that stage when the butt ends of the bristles have been assembled with a ferrule.

Figure 4 is a similar view but showing the pronged plate fixed in place.

Figure 5 is a section on the line 5-5 of Figure 4.

Figure 6 is a section on the line 6-6 of Figure 5.

Figure 7 is a fragmentary section through the brush after assembly with the handle.

Figure 8 is a similar view, but showing a modified form of construction.

Figure 9 is a plan view of a pronged plate suitable for use with an elongated, narrow brush.

Figure 10 is a horizontal section through the ferrule of such a brush, but wherein a multi-piece pronged plate is used.

Before assembling a brush in accordance with the present invention, a bunch or knot of bristles is treated at its butt end portion with a suitable bonding agent, as by dipping thereinto. Various liquid bonding agents such as glue, shellac, or rosin, may be employed for this purpose, but it is preferable to use rubber cements such as so-called rubber solutions or rubber latex, because of their resiliency when they become set. As shown in Figure 3, the butt end portion 1 of the bunch of bristles 2 may then be inserted into one end of an open-ended ferrule 3, preferably made of ductile metal such as steel and having an opening of a size and shape such that the mass of bristles fits nicely therein. The lower end 3a of the ferrule is then contracted as in a suitable die to hold the butt ends of the bristles in place. A thin but rigid metal plate 4 (shown in Figure 2) of a cross-section somewhat smaller than that of the ferrule and having sharp-end prongs 5 struck out in one direction at substantially uniform intervals from its entire body portion, is then passed through the open end 3b of the ferrule, with the prongs pointing in the direction of the bristles, and the prongs are driven into the mass of bristles, as shown in Figure 4 until the plate becomes seated on the butt ends of the bristles. As the prongs are forced into the compressible mass of bristles, the butt ends of the bristles are expanded into tight contact with the interior wall of the ferrule, and they become firmly anchored in this condition when the bonding agent sets or hardens. If a rubber cement is used as the bonding agent, the assembly is preferably heated at this stage to effect a setting and vulcanization of the rubber.

After the plate 4 has been fixed in place, the butt portion 6 of the suitable handle 7 may be driven into the upper end of the ferrule, as shown in Figure 7. The butt end 6 is preferably of such size and configuration that when it is driven home its lower end 6a contacts with the upper face of the plate, and its upper end 6b is substantially flush with the upper end 3b of the ferrule. Preferably, the upper end portion of the ferrule is then contracted to fit snugly against the butt portion 50 of the handle, with its upper end 3b turned over against the upper face of the butt portion to prevent the handle from working loose. In order further to ensure retention of the handle in place, the pronged plate 4 may be provided with sharp end-prongs 8 struck out upwardly therefrom, as shown in Figure 8, so that when the butt portion of the handle is driven home in the ferrule, the prongs 8 will enter thereinto and lock the bristles to the handle.

When brushes of narrow, elongated form are being made, the pronged plate may take a similar form, and in Figure 9 is shown a pronged plate 9 designed for use in this type of brush. Inasmuch as the end portions of

such a brush are its weakest points, it may be desirable to strengthen only these points. In Figure 10 is shown a horizontal section through a ferrule 10 of this type of brush, wherein a comparatively short plate 11 is used at each end portion having prongs 12 struck downwardly therefrom and entering the bristles of the brush at these regions. A pronged plate 13 may also be used at the central zone or portion, so as to prevent weakness of the brush at this zone, where there is maximum tendency for the bristles to buckle and to become loose when they are soaked in water or other liquids which cause their swelling.

I claim:

1. A method of making brushes of the type described, which comprises treating the butt ends of a bunch of bristles with a rubber cement, engaging their ends in one end of a ferrule, passing through the other end of said ferrule a thin but rigid metal plate having prongs struck out therefrom in the direction of the bristles, driving said prongs into said bristles to expand them into tight contact with the interior wall of said ferrule, heating to set and vulcanize the rubber, and fixing the butt end of a handle in the other end of said ferrule.

2. A method of making brushes of the type described, which comprises engaging the butt ends of a bunch of bristles in one end of a ferrule, passing through the other end of said ferrule a thin but rigid metal plate having prongs struck out therefrom in opposite directions, driving those prongs pointing in the direction of the bristles into said bristles, and driving the butt end of a handle into the other end of said ferrule to cause the prongs extending in the opposite direction to enter thereinto.

In testimony whereof I have affixed my signature:

EDWARD M. HILL.
